(57) **CLAIM**

The ornamental design for a table for magnetic resonance imaging (MRI), as shown and described.

DESCRIPTION

FIG. 1 is a front perspective view of a table for magnetic resonance imaging (MRI) showing our new design; FIG. 2 is a front view thereof; FIG. 3 is a rear view thereof; FIG. 4 is a left-side view thereof; FIG. 5 is a right-side view thereof; FIG. 6 is a top view thereof; FIG. 7 is a bottom view thereof; and, FIG. 8 is another perspective view of the table for magnetic resonance imaging (MRI) in which a scanner for magnetic resonance imaging (MRI) is provided in broken lines to illustrate an example environment. The broken lines are for environmental purposes only and form no part of the claimed design.
